ATTORNEY.

UNITED STATES PATENT OFFICE.

DANIEL H. WILCOX, OF BUFFALO, NEW YORK.

CANAL-BOAT.

SPECIFICATION forming part of Letters Patent No. 700,393, dated May 20, 1902.

Application filed December 13, 1901. Serial No. 85,797. (No model.)

To all whom it may concern:

Be it known that I, DANIEL H. WILCOX, a citizen of the United States, residing at Buffalo, in the county of Erie and State of New York, have invented certain new and useful Improvements in Canal-Boats and other Craft; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

15 My invention relates to improvements in canal-boats.

Owing to the peculiar construction of canal-boats there is great danger of damage to the wooden hull and cargo by reason of collisions, 20 striking obstructions on the bottom of the canal, squeezing of the hull during passage through locks and in tows, insufficient calking, or accidental dislodgement of such calking from the seams, which results in inevitable sinking of the boat and consequent destruction of the cargo.

The object of my invention is to prevent the entrance of water into the cargo-space in the event of damage to the wooden hull, there- 30 by insuring the protection of the cargo and preventing the sinking of the boat.

Another and important object of my invention is to increase the structural rigidity of the hull through the stiffening of the sides, 35 ends, and bottom of the boat.

To these ends my invention consists, broadly, in providing the boat with a watertight metallic lining, which is preferably of sectional construction, the sections thereof 40 being both removable and interchangeable.

In the drawings, Figure 1 is a top plan view of a canal-boat embodying my improvements, the deck being removed. Fig. 2 is a longitudinal vertical section of Fig. 1, taken in the 45 line $x-x$. Fig. 3 is an enlarged transverse vertical section of Fig. 2, taken in the line $y-y$; and Fig. 4 is an enlarged fragmentary sectional detail.

Referring to the drawings it will be seen 50 that I have shown my improved construction as applied to an ordinary form of canal-boat, the boats on any one canal being generally

of uniform dimensions and construction, necessarily governed by the depth of water and size of the locks. Of this ordinary construction, as illustrated in the drawings, 1-1 are the bilge-keelsons, and 2 is the center keelson. Between the two bilge-keelsons 1-1 are the transverse floor-timbers 3, set into and secured to the bilge-keelsons. Underneath 55 the floor-timbers 3, and secured thereto, are the bottom-planking 4. The center keelson 2 rests upon and is bolted to the floor-timbers 3. 55 are the side planking, which are secured together and to the bilge-keelsons, by the long bolts 6. (See Fig. 4.)

77 are a series of vertical beams secured at regular intervals to the inner sides of the side planking 5.

The application of my improved lining to 70 the interior of the hull is effected substantially as follows: Assuming the length of the cargo-space between the end collision-bulkheads to be eighty feet, I preferably employ four steel plates 12, each twenty feet in length 75 and of the required thickness, which I removably secure to the vertical beams 7 in any well-known manner. The lower edges of these plates 12 rest upon the bilge-keelsons 1-1, their height being regulated by the water-line of the hull when carrying its maximum load. 11-11 are the end steel plates forming 80 the collision-bulkheads and extending across the entire width of the cargo-space. Resting upon the floor-timbers 3 and on each side of 85 the center keelson 2 are the two series of steel floor-plates 12-12, each four in number, and removably bolted together. These side, end, and floor plates constitute my improved metallic lining for the cargo-space, their inner 90 edges being necessarily water-tight. The junction of the steel plates with the keelsons must also be made water-tight, and this I propose to effect by either the wooden strips 13 or by the angle-irons 14. (See Fig. 4.) The 95 wooden strips 13 are to be slightly beveled on the side next to the metal plates, as at 15, so as to make a secure lodgement for the oakum or other kind of calking. These wooden strips, with supplementary backing-strips 16 on the 100 opposite side of the plate, are to press firmly against the edges of the plate and are to be screwed onto the wooden framework of the boat and then calked between the wooden

strips and the metal plate, thus making the water-tight joint.

If desired, the more expensive joint of the angle-iron 14 can be employed. One important feature of the wooden strips is that they can be easily removed with unskilled labor and without special tools. The same may be said of the angle-irons, which would be riveted to the plates, but which would be screwed to the wooden framework of the boat and would permit of unscrewing with unskilled labor and without special tools. Another important feature is that by this method of removable plates with unskilled labor the owner of the boat can at any time at necessary intervals temporarily remove the plates sufficiently to get at the inner sides of them and coat them with paint to prevent rusting.

It is optional where the collision-bulkheads 20 11 11 are to be placed. If placed as shown in the drawings, then there should be a water-tight door in them, so that cargo could be stored in these spaces. Very likely the boat-owner would prefer the bulkheads to be near 25 the ends of the boat, and this would mean either cutting away each side of the cabin 17 and stable 18, so as to permit of the side plating running the full length of the boat up to these bulkheads, or if the cabin and stable 30 remain as they are then it would be necessary to extend the side plating beyond the cabin and stable, and thus connect with the bulkheads. The spaces 19 between the side planking 5, the side plates 10, and the vertical beams 7 and the similar spaces 20 in the bottom of the hull form water-tight compartments, which in the event of the puncture of the sides and bottom of the hull or the opening of any of the seams will effectually prevent 35 40 the entrance of water within the cargo-space. In the same manner the collision-bulkheads at the bow and stern form water-tight compartments.

It will readily be seen that with my improved construction the steel lining can be 45 easily and quickly removed from one boat and applied to another, and the fact that the plates are of uniform size makes them interchangeable.

My improved construction is particularly 50 applicable to old boats the structures of which have become weak through long and severe usage or where the planking and timbers have been affected by decay, and at the same time 55 the value of a new boat as a freight-carrier is greatly enhanced by the presence of my improved steel lining, which not only serves

to prevent the entrance of water into the cargo-space, but materially increases the structural rigidity of the hull by the additional stiffening of the sides, ends, and bottom of the hull, thus greatly prolonging the useful life of the boat.

I claim—

1. A boat comprising spaced keelsons and 60 transverse floor-timbers, lining-plates disposed with their edges adjacent the keelsons and means removably connected with the keelsons and bearing against the plates for holding the latter against the floor-timbers. 70

2. In a boat, the combination with a keelson and floor-timbers connected thereto, of a lining disposed removably against the floor-timbers and with its edges adjacent the keelson, and means engaged with the keelson and 75 bearing against the lining to hold the latter against the floor-timbers.

3. A boat comprising a keelson and floor-timbers lying at right angles thereto, a lining disposed against the floor-timbers with its 80 edge adjacent the keelson, means removably engaged with the keelson and disposed against the lining to hold the latter against the floor-timbers, and packing disposed between the holding means and the lining. 85

4. A boat comprising a keelson having floor-timbers lying at an angle thereto, a lining disposed against the floor-timbers with its edge against the keelson, a strip disposed in the angle between the lining and keelson and 90 having its face adjacent the lining beveled in the direction of the keelson, packing disposed between the beveled face and the lining and the keelson, and means for holding said strip in said angle. 95

5. A boat comprising a keelson having floor-timbers lying at right angles thereto, a lining disposed against the floor-timbers with its edge adjacent the keelson, a strip disposed in the angle between the lining and keelson and 100 having its face against the lining beveled in the direction of the keelson, packing disposed between the beveled face and the lining and the keelson, means for holding the strip in said angle, and a metallic bulkhead disposed 105 at each end of the boat.

In testimony whereof I have signed my name to this specification in the presence of two subscribing witnesses.

DANIEL H. WILCOX.
